BICYCLE TANK

John F. Day, Englewood, N. J., and Harold F. Maschin, Westfield, Mass., assignors to The Westfield Manufacturing Company, Westfield, Mass., a corporation of Massachusetts

Application April 26, 1951, Serial No. 14,974

Term of patent 7 years

(Cl. D90—8)

To all whom it may concern:

Be it known that we, John F. Day, a citizen of the United States, residing at Englewood, State of New Jersey, and Harold F. Maschin, a citizen of the United States, residing at Westfield, Commonwealth of Massachusetts, have invented a new, original, and ornamental Design for Bicycle Tank, of which the following is a specification, reference being had to the accompanying drawing, forming a part hereof.

Referring to the drawing:

Fig. 1 is a plan view of a bicycle tank, showing our new design;

Fig. 2 is a side elevational view thereof; and

Figs. 3, 4, 5, 6 and 7 are cross-sectional views taken on lines 3—3, 4—4, 5—5, 6—6, and 7—7, respectively, of Fig. 2.

The broken lines shown in the drawing are for illustrative purposes only.

We claim:

The ornamental design for a bicycle tank, substantially as shown and described.

JOHN F. DAY.
HAROLD F. MASCHIN.
